ABSTRACT OF THE DISCLOSURE

A mechanism for use in a copying machine of the type utilizing pre-cut sheets of copy paper in which the copy paper sheets are stored in a supply tray and a sheet is normally maintained in an advanced or pre-fed position. The mechanism pre-feeds the topmost sheet from the supply tray to the advanced position preparatory to a subsequent copying cycle of operation, correlates the operation of feeding components for the copy paper according to varying length of copy paper and document for shortest possible copying time, and controls the operation of a lamp and charger during a current cycle of operation all under the control of switches actuated by the moving document and sheet of copy paper.

Background of the invention

This invention relates generally to improvements in feeding mechanism for copying machines and more particularly to a combined feeding mechanism and timing device for a copying machine utilizing copy paper in the form of cut sheets.

In copying machines of the type which utilize copy paper in cut sheet form as distinguished from roll form, the desirability has been recognized, as evidenced by U.S. Pats. 3,345,926 and 3,352,281, of pre-feeding of sheet of copy paper from a supply stack thereof to an advance or ready position as the final step in a preceding cycle of operation of the copying machine, so that the sheet of copy paper has advanced a predetermined distance along a copy paper path prior to the next copying operation.

The use of cut sheet copy paper is itself desirable in low cost copying machines since the need for a cutting mechanism as well as suitable controls for operating the cutting mechanism is eliminated. Also, cut sheet storage is more compact than roll paper storage, which is important in a relatively small desk top type copying machine. However, a major disadvantage in the use of cut sheet copy paper in most prior art copying machines is in the increased length of time required to make a single copy of an original document from the moment the document is inserted into the copying machine until the finished copy is delivered. The reason for this is that, in the design of the copier, it usually is not possible to locate the copy paper storage tray in a position which places the leading edge of the stack of paper as close to the copying components as is possible with a roll type copying machine, thereby increasing the length of the copy paper path and the time required to move a sheet through the path.

For example, in a machine utilizing roll paper, the roll can be stored in any desirable location with a web portion thereof leading to a cutting mechanism located immediately adjacent the copying components, e.g. the charger in an electrostatic type copying machine. In a cut sheet machine, however, design characteristics often require that the copy paper supply tray be disposed adjacent an edge of the copying machine with the charger

2

a considerable distance therefrom due to the configuration of the optical system and the desirability of keeping the charger as close as possible to the exposure area. Also, sufficient space must be allocated between the front edge of the supply tray and the charger for at least one pair of feed rollers which feed the sheet into the charger. Further, the design must provide for a level paper tray which is convenient for operator access for loading.

A practical solution to the problem of the increased length of time required to obtain a copy from a cut sheet type copying machine, as against the shorter time required to make the same copy in a roll paper type machine, is to normally store a sheet of copy paper in an advanced or ready position with its leading edge disposed as close as possible to the copying components of the machine. As shown in the above mentioned U.S. patents, this is most desirably accomplished by providing means for separating and feeding the topmost sheet of the stack of copy paper from the stack storage location to the ready position as a final step incident to a complete cycle of operation of the copying machine, or at least as an intermediate step while a preceding copy is being developed and delivered to the machine operator. Thus the time required to pre-feed the sheet of copy paper from the stack to the ready position is absorbed in the normal time required to process the copy made on a preceding sheet of paper, and is not made cumulative with the normal processing time for making a copy.

The present invention is directed to improve means for feeding a sheet of copy paper from a stack thereof to an advanced or ready position in the copying machine, and in this regard, constitutes an improvement on the corresponding means of the above mentioned patents. It is known to control the advance of a sheet of copy paper for a predetermined distance only under the control of a plurality of paper actuated switches which in turn control the operation of electric motors and/or clutches to start and stop a plurality of paper feeding devices according to a predetermined program. A major disadvantage of this arrangement resides in the relatively large number of paper actuated switches which must be employed to control the stopping and starting of the copy paper feeding mechanism to move a sheet over the required distance. Paper actuated switches are not only expensive due to their high degree of sensitivity, but also they are frequently a source of trouble due to the possibility of causing paper jams. This latter aspect is particularly undesirable in the copy paper path where it requires a considerable amount of disassembly of the machine to clear a jammed sheet of paper. In general, the more that paper actuated switches can be eliminated, the greater is the degree of reliability of trouble free operation of the copying machine.

Brief summary of the invention

The present invention obviates the foregoing disadvantages of prior art cut sheet type copying machines by providing a relatively simple yet reliable mechanical device for controlling both the time sequence and distance of pre-feeding of a sheet of copy paper. In addition, the device of the present invention also controls the instant and duration of energization of an illumination lamp and a corona discharge unit, thereby still further reducing the need for paper actuated switches which control this function in the known machines.

According to one embodiment of the present invention, there is provided a copying machine having a storage means for a stack of sheet of copy paper, a guiding and transporting means defining a path of travel having an infeed end adjacent the storage means and extending through the copying machine, means for continuously driving the transporting means, and means defining an

exposure zone spaced along the path of travel in which a sheet of copy paper is exposed to an image of indicia on an original document. In this combination the present invention is directed toward a mechanism for successively feeding sheets of copy paper from the storage means to the guiding and transporting means and comprises a first feeding means disposed adjacent the storage means for feeding the topmost sheet from the stack into the infeed end of the guiding means, and a second feeding means spaced along the path of travel between the infeed end thereof and the exposure zone, the second feeding means, which is preferably a pair of intermittently driven feed rollers, defining an advanced position for the leading edge of a sheet of copy paper. A clutch means is provided for alternately connecting the driving means to the first and second feeding means, the clutch means being operative to connect the driving means to the second feeding means at the beginning of a copying cycle of operation of the copying machine and to the first feeding means after the trailing edge of the sheet has passed the second feeding means. In order to control the movement of the sheet of copy paper there is provided means operatively associated with the clutch means and with the first feeding means for limiting the operation of the first feeding means, during the time that the clutch means is operative to connect the driving means to the first feeding means, to feed a sheet of paper from the storage means substantially only a distance sufficient to bring the leading edge of the sheet into operative engagement with the second feeding means, with the result that the sheet is moved from the storage means only to the advanced position and not beyond preparatory to a subsequent copying cycle of operation of the copying machine.

A significant aspect of the present invention is the fact that the clutch means is responsive to operation of a control means in the copying machine which may be either manually operated or may be operated automatically by sensing the leading and trailing edges of an original document. Thus the present invention is applicable both to book copiers where the original is merely placed on a platform for illumination and a copying cycle of the machine is initiated by a manual control, as well as to strictly document copiers where the document is inserted into a transporting system and the document itself automatically initiates a copying cycle of operation of the machine.

As will be made more clear hereinafter, the simplicity and reliability of the device of the present invention resides in the fact that the lead edge of the copy paper sheet is engaged preferably in the nip of a pair of feed rollers which are driven by the clutch means in synchronism with the main copy paper transport system only on demand as controlled by a manual or automatic control, these feed rollers becoming inoperative and thereby conditioned to receive the leading edge of the next sheet of copy paper as soon as the trailing edge of the previous sheet has passed by these feed rollers.

An advantageous feature of this invention resides in the fact that a mechanical motion of the means limiting the operation of the first feeding means to a feed a sheet only to the advanced position is utilized to control the energization of an illuminating lamp and copy paper charger so that further elimination of paper actuated switches to control these functions is achieved.

Having briefly described one embodiment of the present invention, it is a principal object thereof to provide a new and improved copy paper feeding mechanism for copying machines.

It is another object of the present invention to provide a copy paper feeding mechanism for copying machines which accurately pre-feeds a sheet of copy paper from a paper storage position to an advanced or ready position.

It is another object of the present invention to provide a copy paper feeding mechanism for copying machines which pre-feeds a sheet of copy paper from a storage position to an advanced or ready position as an intermedi-

ate or terminal step in the cycle of operation of the copying machine during which a copy is being made on a previously fed sheet of copy paper.

It is still another object of the present invention to provide a copy paper feeding mechanism for a copying machine which is operable to both advance a sheet of copy paper from a ready position into the copy paper transport system and to pre-feed the next sheet of copy paper from a storage position to the ready position in response to operation of either a manual or automatic paper actuated control.

It is yet another object of the present invention to provide a copy paper feeding mechanism for a copying machine which is operable to control the instant and duration of energization of an illuminating lamp and copy paper charger without the necessity of any additional paper actuated switches.

A further object of the present invention is to provide a copy paper feeding mechanism for a copying machine which has provision for sensing the length of copy paper sheets and documents being copied and for controlling the sequence of operation of feeding components to deliver copy in the shortest possible time.

It is a further object of the present invention to provide a copy paper feeding mechanism for a copying machine which is extremely simple in design and construction, is highly reliable and accurate in operation and is economical to manufacture.

These and other objects and advantages of the present invention will be more readily apparent from an understanding of the following detailed description of one embodiment of the present invention when considered in conjunction with the accompanying drawings in which:

FIG. 1 is a longitudinal sectional view through a copying machine embodying the present invention;

FIG. 2 is a side elevation drawn to an enlarged scale of the copy paper feeding mechanism of the present invention;

FIG. 3 is a side elevation of the one revolution drive element of the mechanism shown in FIG. 2; and

FIG. 4 is a view taken on the line 4—4 of FIG. 3.

Detailed description

Referring now to the drawings and particularly to FIG. 1 thereof, there is shown in diagrammatic form a copying machine 10 of the second type above mentioned wherein an original document is transported through the machine and in which the present invention may be utilized. Although a considerable amount of detail of construction has been omitted from FIG. 1 for the sake of clarity, which detail either forms no part of the present invention or is obvious to anyone skilled in the art to which the present invention relates, the figure nevertheless shows all of the major working components of an electrostatic copying machine with sufficient particularity to obtain a full and complete understanding of the paper feeding mechanism of the present invention.

More particularly, there is provided a generally rectangular frame comprising a pair of upstanding parallel side plates 12 and 14 (plate 14 being shown in FIG. 2) between which all of the interior components of the copying machine are mounted. Certain other components to be described hereinafter are mounted on the outside of plate 14, and in practice the entire frame is covered with a suitable housing having access openings for ingress and egress of documents to be copied and for egress of copies.

A plate 16 suitably supported by the frame plates 12 and 14 and associated with an opening in the aforementioned housing defines an inlet guideway for original documents to be copied, and directs the leading edge of a document to the nip of a pair of feed rollers 18 and 20 rotatably supported by the plates 12 and 14. A pair of substantially vertical guide plates 22 and 24 define a portion of a document feed path which extend downwardly along the front edge of the copying machine. Another pair of guide

plates 26 and 28 define another portion of the document feed path which includes an illuminating station or zone defined by an elongate slit 30 formed in the guide plate 26. Adjacent the lower end of the guide plates 26 and 28 is another pair of feed rollers 32 and 34 which direct the document between the curved guide plates 36 and 38 which in turn direct the document out of the copying machine. All of the foregoing elements together define a guiding and transporting means for the original documents.

The pairs of feed rollers 18-20 and 32-34 are synchronously driven by means of a continuous moving drive chain 40, a portion of which is shown in FIG. 2. As will be more clear hereinafter, the chain 40 is driven by a suitable motor conveniently located in the copying machine, the chain 40 passing around suitable sprockets and gears connected to a plurality of sets of feed rollers and also passing around suitable idler sprockets in order to drive the feed rollers synchronously in a manner well known in the art. Only the sets of feed rollers specifically mentioned below are not directly driven by the chain 40.

In order to project an image of indicia on an original document to a sheet of copy paper for copying, an optical system is provided which comprises a source of illumination in the form of a lamp 42 and a projecting shield 44 which concentrates the light from the lamp 42 on the illuminating station defined by the slit 30 in the guide plate 26. Rays of light are reflected from a document passing by the slit 30 to a mirror 46 which directs the rays of light through a focusing lens 48 to a reflex lens 50 having a reflecting surface 52. The rays of light are then reflected back through the focusing lens 48 to another mirror 54 which directs the rays of light to an elongate slit 56 formed in a guide plate 58 which, together with a juxtaposed guide plate 60, defines an exposing station or zone for a sheet of copy paper which is fed between the guide plates 58 and 60 by means hereinafter described. It will be apparent to those skilled in the art that all of the foregoing elements of the optical system are suitably supported in the positions shown in FIG. 1 by mountings or brackets which are connected, directly or indirectly, to the frame plates 12 and 14.

The guide plates 58 and 60 are part of a guiding and transporting means defining a path of travel through which sheets of copy paper are fed from a supply thereof through a charging device, the exposing station, and through a developing and drying station to a discharge location accessible to an operator. More particularly, a stack of copy paper 62 is supported by a copy paper storage tray 64 which is pivotally supported by a shaft 66 mounted in the frame plates 12 and 14. A spring 68 connected at one end 70 to one of the frame plates and at the other end 72 to the rear end of the copy paper tray 64 urges the tray 64 in a clockwise direction about the shaft 66. The tray 64 is provided with a side guide 74 along each side of the tray 64 which centers the stack 62 of copy paper, and a corner separator 76 of known construction is mounted on the front corners of the tray 64 to assist in separating the topmost sheet from the rest of the stack when the sheet is fed in a manner described herein-after.

Positioned adjacent the front end of the paper supply tray 64 is a first guide plate 78 and a second juxtaposed guide plate 80, the guide plates 78 and 80 being suitably shaped so as to provide a relatively wide infeed opening 81 into the copy paper path of travel and to define a gradually restricted path which leads into a vertical portion to thereby direct the leading edge of a sheet of copy paper to the nip of a pair of feed rollers 82 and 84. This pair of feed rollers, which is a second feeding means of the invention as hereinafter more fully described, defines an advanced position to which a sheet of paper is initially fed from the storage tray 64.

Located downwardly from the feed rollers 82 and 84 is a corona discharge device 86 of known construction

which imparts a uniform electrostatic charge to the sheet of copy paper passing therethrough. A pair of feed rollers 88 and 90 feeds the sheet of copy paper from the exposing station 56 into a developing tank 92 which contains a suitable toner for developing the latent electrostatic image left on the copy paper after it passes the exposing station 56. Suitable guide elements 94 and 96 guide the sheet of copy paper through the toner tank 92 and direct the leading edge of the sheet to another pair of feeding rollers 98 and 100 which also act as squeegee rollers to squeeze all excess toner off of the copy paper. A pair of juxtaposed guide plates 102 and 104 guide the sheet of paper through a drying zone and to a final pair of feed rollers 106 and 108 which deliver the copy sheet to a receiving tray 110 in which the finished copy sheet is accessible to an operator through an opening 112 formed in the front of the housing.

Coming now to the mechanism for successively feeding sheets of copy paper from the storage tray to the copy paper guiding and transporting means so that the leading edge thereof arrives at the exposing station in synchronization with the arrival of the leading edge of an original document at the illuminating station, and referring first to FIG. 1, there is shown a first feeding means comprising a shaft 120 rotatably supported by the side plates 12 and 14 in a position overlying the forward or feeding end of the paper storage tray 64. The shaft 120 fixedly carries at least one feed roller 122 and preferably a plurality of feed rollers which, when rotated by the shaft 120, feed the topmost sheet from the stack 62 into the infeed end of the copy paper path hereinabove described. The shaft 120 carries a gear 124 located on the outer side of the frame plates 14 and therefore is shown in phantom lines in FIG. 1 and in solid lines in FIG. 2. Additional portions of the copy paper feeding mechanism are also shown in phantom lines in FIG. 1 for the sake of relating the location of the structure shown in FIG. 2 to the rest of the copying machine shown in FIG. 1. The gear 124 is drivingly connected to the shaft 120 by any suitable overriding or one way drive means so that the shaft 120 and feed rollers 122 are driven in a clockwise direction as viewed in the figures when the gear 124 is driven in the same direction, but the feed rollers 122 and shaft 120 can rotate in a clockwise direction independently of rotation of the gear 124. Thus after the feed rollers 122 have fed the sheet a predetermined distance to the advanced position defined by the feed rollers 82 and 84, the latter when actuated as hereinafter described, can pull the remainder of the sheet from the storage tray 64 without altering the position of the gear 124 and other elements associated therewith as fully explained below.

Referring to FIG. 2, it will be seen that the chain 40, which it will be recalled is continuously driven during the time that the copying machine is in an "on" conditions, passes around a floating idler sprocket 126 which is urged downwardly by a tension spring 128 connected between the idler sprocket shaft 130 and the frame plate 14, thereby maintaining proper tension on the chain 40. The chain also passes around and drives a sprocket 132 rotatably carried by a stub shaft 134 mounted on the plate 14. A gear 136 is rigidly connected to the sprocket 132 for rotation therewith.

In order to alternately connect the driving means to the first and second feeding means, there is provided a clutch means which, in the preferred embodiment, comprises a lever 138 pivotally carried by the stub shaft 134 and having a tail portion 140 to which is connected a spring 142 which urges the lever 138 in a clockwise direction about the stub shaft 134 and normally maintains the tail portion 140 in contact with an adjustable stop member 144. A solenoid 146 has its core 148 connected to the lever 138 intermediate the shaft 134 and the tail portion 140 so that when the solenoid is energized the lever 138 is pivoted about the shaft 134 in a counter-

clockwise direction against the restoring force of the spring 142. Energization and deenergization of the solenoid 146 is controlled preferably by paper sensing switches in a manner described below.

The lever 138 rotatably carries a first gear 150 which meshes with the gear 136, and a second gear 152 which meshes with the gear 150 whereby rotation of the gear 136 by the drive chain 40 also drives the gear 152. The gear 152 is adapted to mesh alternately with a gear 154 fixedly carried by an extension of the shaft 156 on which the feed roller 84 is mounted, and another gear generally designated 158 rotatably carried by a stub shaft 160 mounted on the plate 14. Thus the lever 138, the solenoid 146, the spring 142 and the gears 136, 150 and 152 all constitute a paper actuated clutch means for alternately connecting the drive chain 40 into driving engagement with the gear 154 or the gear 158, the clutch means being in the former condition to drive the feed rollers 82 and 84 when the solenoid 146 is energized and being in the latter condition to drive the gear 158 when the solenoid 146 is deenergized.

The gear 158 is actually an intermittently operable drive transfer element and forms part of a means for limiting operation of the feed rollers 122, even while the clutch means is in its normal position to connect the driving means to the feed rollers 122, to feed a sheet only the predetermined distance between the supply tray 64 and the advanced position. In the preferred embodiment, this drive element is a partially mutilated gear which is adapted to make one revolution in response to engagement therewith by the gear 152, after which the element 158 stops turning until the gear 152 is released from engagement with the element 158 by the clutch means and is reengaged therewith after a certain period of engagement with the gear 154. By operation of this element, the rollers 122 are effective to pre-feed the topmost sheet of copy paper from the stack to a position where the lead edge of said sheet is in contact with the nip of the feed rollers 82 and 84, after which the rollers 122 stop feeding even though the gear 152 of the clutch means remains engaged with the drive transfer element 158.

More particularly, and referring to FIGS. 2-4, the element 158 comprises a disc 162 having an annular rim 164 with teeth 166 formed thereon which extend across the width of the rim 164. A recess 168 is formed in the rim adjacent one side thereof, the recess extending across approximately one-half the width of the rim 164. The gear 152 is approximately the same width or a little less than the depth of the recess 168 and is mounted on the lever 138 so as to be in alignment with the recess 168 with the result that the teeth of the gear 152 do not mesh with the teeth 166 of the element 158 when the recess 168 is adjacent the gear 152. Thus the gear 152 cannot drive the element 158 even though the solenoid 146 is deenergized until the element 158 is rotated by other means to move the recess 168 away from the position shown in FIG. 2.

The element 158 is also provided with a semi-circular stud 170 which projects outwardly from the outer face of the element 158 as viewed in FIG. 2, the stud 170 making contact with a nose 172 formed on the end of the lever 138 to thereby prevent rotation of the element 158 until the lever 138 is rocked by energization of the solenoid 146. The element 158 is also provided with a cam track 174 formed on the inner surface of the element 158, the cam track following a circular path adjacent the rim 164 for most of the circumference of the cam track, but having a somewhat radially inwardly extending flat portion 176 disposed in angularly offset relationship with the recess 168 and terminating in a curved detent portion 177.

A spring loaded actuator in the form of a lever 178 is pivotally carried by a stud 180 mounted on the frame plate 14, the lever 168 rotatably carrying a cam follower roller 182 adjacent the cam track 174. A tension spring

184 connected between the opposite end of the lever 168 and the frame plate 14 forcibly urges the lever in a clockwise direction about the pivot stud 180 so as to maintain firm contact between the roller 182 and the cam track 174.

5 The operation of the drive transfer element 158 in conjunction with the clutch means described above is as follows: When the solenoid 146 is energized by means described below, the lever 138 is rocked counterclockwise about the stub shaft 134 to simultaneously move the nose 172 out of contact with the stud 170 on the element 158, and to engage the gear 152 with the gear 154, thereby driving the feed rollers 82 and 84, since, it will be remembered, the chain 40, sprocket 182, and gears 136, 150 and 152 are continuously rotating. As soon as the nose 172 moves beyond the stud 170, the roller 182, bearing on the flat 176 of the cam track 174, moves the gear 158 through a small angular distance until the roller 182 comes to rest in the detent portion 177 but sufficient to move the recess 168 away from its position adjacent the element 152. This movement of the element 158 is caused by the upward force exerted on the flat portion 176 of the cam track 174 by the roller 182 as a result of the strong pulling force of the spring 184 acting through the lever 178.

When the solenoid 146 is deenergized, the spring 142 returns the lever 138 to the position shown in FIG. 2 whereupon the gear 152 is disengaged from the gear 154 and is engaged in driving relationship with the teeth 166 of the drive transfer element 158 to rotate the latter. Rotation of the element 158 rotates the gear 124 which rotates the shaft 120 through the one way drive means mentioned above which in turn rotates the feed rollers 122. This continues until the recess 168 again comes around to a position adjacent the gear 152 at which point the gear 152 ceases to have driving engagement with the element 158, and the stud 170 is again in engagement with the nose 172 of the lever 138. Also, during rotation of the element 158 the cam follower roller 182 has been following the circular portion of the cam track 174. The location of the recess 168 and the flat portion 176 just before the teeth of the gear 162 disengage from the teeth 166 of the element 158 so that the roller 182 moves a short distance along the flat portion 176 of the cam track. This is to assure that the roller 182 will maintain the stud 170 in engagement with the nose 172 of the lever 138 so as to properly position the recess 168 adjacent the gear 152 and prevent any binding or scraping of the teeth of the gear 152 and the element 158 when the latter is in its static condition. Thus it will be seen that the element 158 makes one complete revolution each time the solenoid 146 is energized and deenergized. The relative diameters of the element 158 and gear 124, and the feed rollers 122, are selected so that the topmost sheet of copy paper is fed a distance sufficient to move the lead edge of the sheet from its normal position in the stack to a position of engagement with the nip of the feed rollers 82 and 84 during the same one revolution of the element 158.

60 In order to relate the operation of the above described clutch mechanism and the first and second copy paper feeding means to the overall operation of the copying machine 10, reference will now be made to FIG. 1. It will be seen that a control means in the form of a switch 190 is located adjacent the entrance to the original document path, the switch 190 having a paper sensing actuator 192 disposed in the document path. The actuator 192 is located upstream from the illuminating area 30 a distance approximately equal to the distance between the exposing area 56 and the nip of the feed rollers 82 and 84 in order to assure that the leading edges of the original document and the copy paper arrive at the illuminating and exposing areas respectively at the same time.

The switch 190 controls the energization of the solenoid 75 146 to energize the latter in response to operation of the

switch 190 by the leading edge of a document and to de-energize the solenoid in response to operation of the switch 190 by the trailing edge of the document. Assuming that the document is the same length as the copy paper stored in the machine, it will be understood that the trailing edge of the document will actuate the switch 190 to de-energize the solenoid 146 at about the same instant that the trailing edge of the sheet of copy paper leaves the nip of the rollers 82 and 84. A second switch 194 is located in the copy paper path adjacent the feed rollers 82 and 84 and has a paper sensing actuator 196 disposed in the paper path. This switch is connected to the solenoid 146 in parallel with the switch 190 in order to assure that the copy paper feed mechanism will run a full normal cycle of operation even if an original document is inserted into the machine which is shorter than the length of copy paper in the stack 62, since the copy paper feeding mechanism is intended to feed a standard size sheet of paper. Also, the switches 190 and 194 combine in function to control the operation of the clutch means and hence the first and second feeding means to deliver a copy in the shortest possible time. This is particularly so when making multiple copies or successive copies.

A significant feature of the present invention is the utilization of the motion of the drive transfer element 158 to control the energization and deenergization of the lamp 42 and the charger 86 in synchronism with the initiation of a copying cycle of operation and with passage of the trailing edge of a document and a sheet of copy paper through the illuminating and exposing areas respectively. Thus, a third switch 198 (FIG. 2) is mounted on the plate 14 and has an actuator finger 200 extending toward the element 158 and lying in a position to be alternately moved and released by a stud 202 which projects from the rear face of the element 158 in axial alignment with the stud 170 projecting from the front face of the element 158. The actuator finger 200 terminates at the stud 202 so that it is released for movement away from the switch 198 as soon as the element 158 is rotated the small angular movement by the roller 182 and the spring loaded lever 168. This movement of the actuator finger 200 closes the switch 198 which closes suitable circuits to energize the illuminating lamp 42 and the copy paper charger 86. The switch 198 remains closed until the element 158 completes its copy paper driving movement after the solenoid 146 is deenergized and returns to the position shown in FIG. 2, whereupon the stud 202 again engages the actuator finger 200 to open the switch 198, thereby turning off the lamp and charger. Thus it will be seen that the element 158 which controls the copy paper pre-feed function also functions as a timing device to control the moment and duration of energization of the lamp and charger during a normal copying cycle of the machine, and assures that the lamp and charger will remain energized until the document and copy paper have cleared their respective illuminating and exposing areas.

A complete cycle of operation of the copying machine will now be described with reference to the drawings. An original document is placed on the shelf 16 from which it slides into the nip of the feed rollers 18 and 20. After being picked up by the feed rollers, the leading edge of the document closes the switch 190 which energizes the solenoid 146 to shift the clutch mechanism into driving engagement with the gear 154. The rollers 82 and 84 then begin to feed the sheet of copy paper which has been pre-fed to the advanced position where the leading edge of the sheet is engaged in the nip of the rollers 82 and 84 during the previous cycle of operation of the machine 10.

As soon as the clutch mechanism shifts, the drive transfer element 158 rotates slightly so that the stud 202 releases the actuator finger 200 whereupon the switch 198 turns on the lamp 42 and the charger 86. The original document and the sheet of copy paper advance in synchronism through their respective paths, the copy paper

first passing through the charger 86 and then through the exposing area while the document is approaching and passing through the illuminating area. When the feed rollers 82 and 84 initially feed the copy paper sheet, the trailing end portion of the sheet which is still overlying the stack pulls the feed rollers 122 in the feeding direction by virtue of the one way drive connection between the gear 124 and the shaft 120.

The clutch mechanism is held in driving engagement with the gear 154 until the trailing end of the document actuates the switch 190 or the trailing end of the copy paper sheet actuates the switch 194, whichever occurs later, at which time the solenoid 146 is deenergized and the clutch mechanism shifts back to its spring loaded position. The gear 152 then drives the element 158 through one revolution in the manner explained above, during which time the gear 124, the one way drive means, the shaft 120 and the rollers 122 feed the next sheet of copy paper into the copy paper path until the leading edge thereof is in the nip of the feed rollers 82 and 84. At this point the stud 202 will again engage the actuator finger 200 to close the switch 198 to turn off the lamp and charger, but by this time the trailing edges of both the document and the sheet of copy paper have cleared their respective illuminating and exposing areas. The original document is directed out of the machine by the guide plates 36 and 38 while the exposed copy sheet continues through the toner tank 92 for developing and is directed to the discharge receiving tray 110. The copying machine is ready for another copying cycle of operation as soon as the element 158 has completed one revolution and returned to its home position which condition may be conveniently indicated by an indicator light suitably wired through other contacts of the switch 198.

As a practical matter, the dimensions of the feed rollers 122 and driving gear 124 are selected so that in the course of one revolution of the drive transfer element 158, the rollers 122 feed a greater length of a sheet of copy paper than is necessary to bring the leading edge thereof to the nip of the feed rollers 82 and 84. The reason for this is to create a bend or curved buckle in the sheet in the area of the entrance opening 81 to the copy paper path so as to assure that the leading edge of the sheet will not be skewed when it is fed into the charger 86, and finally so that the sheet remains in the proper advanced position for long periods of time if necessary to await the next copying cycle of operation of the copying machine.

It has been indicated briefly above that the present invention has applicability to a book-type copying machine as well as to a sheet-type machine. In the specific embodiment of the copying machine described above and shown in the accompanying drawings, it will now be recognized that the switch 190 may be replaced by a manually operable "start" switch which is actuated after a book or any flat document has been placed in position on the illuminating component of the machine. This may be a stationary transparent platform beneath which a traveling light source scans the book or document, or the platform may travel back and forth relative to a stationary light source, both of which arrangements are well known in the art.

When the equivalent "start" switch 190 is actuated manually, the same sequence of operation of the copy paper feeding mechanism takes place as fully described above, with the exception that it is now necessary to have the switch 194 in the copy paper path to keep the solenoid 146 energized for the proper length of time since the "start" switch would be only momentarily closed to energize the solenoid 146 and cause the feed rollers 82 and 84 to feed the sheet far enough to close the switch 194. Alternatively a secondary control for the solenoid 146 may be associated with the mechanical movement either of the document platform or the lamp as the case may be.

11

It is now apparent from the foregoing that there has been provided a combined copy-paper pre-feed and timing mechanism for copying machines which avoids the disadvantages of prior art copying machines and which achieves the foregoing objects. It is to be understood that the present invention is not intended to be limited to the specific embodiment described above and shown in the accompanying drawings, which is merely illustrative of the principles of the invention and is the best mode presently contemplated for carrying out the invention, and is susceptible to change in form, size, detail and arrangement of parts, the invention being intended to cover all such equivalents, variations and modifications thereof as may be deemed to be within the scope of the claims appended hereto.

I claim:

1. In a copying machine having storage means for a stack of sheets of copy paper, guiding and transporting means defining a path of travel for sheets of copy paper having an infeed end adjacent said storage means and extending through the copying machine, means for continuously driving said transporting means, and means defining an exposure zone spaced along said path of travel in which a sheet of copy paper is exposed to an image of indicia on an original document, the combination therewith of a mechanism for successively feeding sheets of copy paper from said storage means to said guiding and transporting means, said mechanism comprising

- (A) first feeding means disposed adjacent said storage means for feeding the topmost sheet from said stack into said infeed end of said guiding means,
- (B) second feeding means spaced along said path of travel intermediate said infeed end thereof and said exposure zone, said second feeding means defining an advanced position for the leading edge of a sheet of copy paper,
- (C) clutch means for alternately connecting said driving means to said first and second feeding means and being operative to connect said driving means to said second feeding means at the beginning of a copying cycle of operation of the copying machine and to said first feeding means after the trailing edge of a sheet has passed said second feeding means, and
- (D) means operatively associated with said clutch means and said first feeding means for limiting the operation of said first feeding means, while said clutch means is operative to connect said driving means to said first feeding means, to feed a sheet of paper from said storage means substantially only a distance sufficient to bring the leading edge of said sheet into operative engagement with said second feeding means whereby said sheet is moved from said storage means to said advanced position preparatory to a subsequent copying cycle of operation of the copying machine.

2. A combination according to claim 1 wherein said means limiting the operation of said first feeding means comprises an intermittently operable drive transfer element coacting between said clutch means and said first feeding means and having means for automatically disengaging said driving means from said first feeding means without disengaging said clutch means from said drive transfer element when the leading edge of said sheet has been moved to said advanced position.

3. A combination according to claim 2 wherein said means for limiting the operation of said first feeding means further comprises a yieldable means operable upon disengagement of said clutch means from said drive transfer element to move said drive transfer element to a position where said driving means is reengaged with said first feeding means upon reengagement of said clutch means with said drive transfer element whereby said first feeding means is operated subsequent to said second feeding means during a cycle of operation of said copying machine.

4. A combination according to claim 2 wherein said first feeding means includes one way drive means coacting

12

with said drive transfer element whereby said second feeding means can withdraw the remainder of a sheet of paper from said storage means without altering the position of said drive transfer element.

5. In a copying machine having storage means for a stack of sheets of copy paper, guiding and transporting means defining a path of travel for sheets of copy paper having an infeed end adjacent said storage means and extending through the copying machine, means for continuously driving said transporting means, and means defining an exposure zone spaced along said path of travel in which a sheet of copy paper is exposed to an image of indicia on an original document, the combination therewith of a mechanism for successively feeding sheets of copy paper from said storage means to said guiding and transporting means, said mechanism comprising

- (A) first feeding means disposed adjacent said storage means for feeding the topmost sheet from said stack into said infeed end of said guiding means,
- (B) second feeding means spaced along said path of travel intermediate said infeed end thereof and said exposure zone, said second feeding means defining an advanced position for the leading edge of a sheet of copy paper,
- (C) control means in said copying machine for initiating a copying cycle of operation and for sensing when the trailing edge of a sheet of copy paper has passed said second feeding means,
- (D) clutch means responsive to said control means for alternately connecting said driving means to said first and second feeding means, said clutch means being responsive to operation of said control means when initiating a copying cycle of operation to connect said driving means to said second feeding means and being responsive to operation of said control means when sensing the movement of the trailing edge of a sheet past said second feeding means to connect said driving means to said first feeding means, and
- (E) means operatively associated with said clutch means and said first feeding means for limiting the operation of said first feeding means, while said clutch means is operative to connect said driving means to said first feeding means, to feed a sheet of paper from said storage means substantially only a distance sufficient to bring the leading edge of said sheet into operative engagement with said second feeding means whereby said sheet is moved from said storage means to said advanced position preparatory to a subsequent copying cycle of operation of the copying machine.

6. A combination according to claim 5 wherein said means limiting the operation of said first feeding means comprises an intermittently operable drive transfer element coacting between said clutch means and said first feeding means and having means for automatically disengaging said driving means from said first feeding means independently of operation of said control means when the leading edge of said sheet has been moved to said advanced position.

7. A combination according to claim 6 wherein said drive transfer element comprises a one revolution rotary drive member engaged between said clutch means and said first feeding means, said drive member having means for effecting a driving engagement between said clutch means and said first feeding means disposed over only a major portion of the periphery of said drive member and having a minor portion of said periphery formed to interrupt said driving engagement.

8. A combination according to claim 7 wherein said drive member is a gear having circumferential teeth which mesh with the teeth of a gear defining the output of said clutch means and another gear connected to said first feeding means, said drive member gear having an arcuate recess in the teeth thereof which extends axially over a portion of the length of said teeth, the teeth of said clutch output gear being no longer than the depth of said recess in said drive member gear and being aligned with

said recess whereby said clutch output gear stops driving said drive member gear when said recess registers with said clutch output gear.

9. A combination according to claim 8 wherein said drive member gear includes stop means adapted to engage a portion of said clutch means when the latter is engaged with said drive member gear, said stop means being spaced in relation to said recess to positively arrest movement of said drive member gear when said recess registers with said clutch output gear.

10. A combination according to claim 6 wherein said means for limiting the operation of said first feeding means further comprises a spring loaded actuator operable in response to operation of said control means when initiating a cycle of operation of the copying machine to move said drive transfer element to a position where said driving means is reengaged with said first feeding means when said control means operates upon sensing the movement of the trailing edge of the sheet of copy paper past said second feeding means whereby said first feeding means is operated subsequent to said second feeding means during a copying cycle of operation of said copying machine.

11. A combination according to claim 10 wherein said drive transfer element comprises a one revolution rotary drive member engaged between said clutch means and said first feeding means, said drive member having means for effecting a driving engagement between said clutch means disposed over only a major portion of the periphery of said drive member and having a minor portion of said periphery formed to interrupt said driving engagement, said drive member further having cam means cooperating with said spring loaded actuator for moving said drive member only a distance sufficient to dispose said minor portion of the periphery of said drive member out of operative association with said clutch means.

12. A combination according to claim 11 wherein said drive member is a gear having circumferential teeth which mesh with the teeth of a gear defining the output of said clutch means and another gear connected to said first feeding means, said drive member gear having an arcuate recess in the teeth thereof which extends axially over a portion of the length of said teeth, the teeth of said clutch output gear being no longer than the depth of said recess in said drive member gear and being aligned with said recess, said cam means having a portion aligned with said recess for moving said gear to a position where said recess is disposed away from said clutch output gear whereby said clutch output gear stops driving said drive member gear when said recess registers with said clutch output gear and said recess is moved out of registration with said clutch output gear when said clutch means is again engaged with said second feeding means.

13. A combination according to claim 12 wherein said drive member gear includes stop means adapted to engage a portion of said clutch means when the latter is engaged with said drive member gear, said stop means being spaced in relation to said recess and to said portion of said cam means aligned with said recess to positively arrest movement of said drive member gear when said recess registers with said clutch output gear and to prevent said spring loaded actuator from moving said drive member gear while said clutch output gear is engaged with said recess of said drive member gear.

14. In a copying machine having storage means for a stack of sheets of copy paper, first guiding and transporting means defining a first path of travel for sheets of copy paper having an infeed end adjacent said storage means and extending through the copying machine, second guiding and transporting means defining a second path of travel for original documents through the copying machine, means for continuously driving said first and second transporting means in synchronism, and means defining an exposing zone and an illuminating zone spaced along said first and second paths of travel respectively in which

a sheet of copy paper is exposed to an image of indicia on an original document, the combination therewith of a mechanism for successively feeding sheets of copy paper from said storage means to said first guiding and transporting means, said mechanism comprising

5 (A) first feeding means disposed adjacent said storage means for feeding the topmost sheet from said stack into said infeed end of said first guiding means,
 (B) second feeding means spaced along said first path of travel intermediate said infeed end thereof and said exposure zone, said second feeding means defining an advanced position for the leading edge of a sheet of copy paper.

10 (C) control means including sensing means located in said second path of travel and spaced from said illuminating zone a distance substantially equal to the distance between said second feeding means and said exposure zone in said first path of travel, said sensing means being operative to sense the leading edge of a document to actuate said control means to initiate a copying cycle of operation of the copying machine and operative to sense the passage of the trailing edge of the document,

15 (D) clutch means responsive to said control means for alternately connecting said driving means to said first and second feeding means, said clutch means being responsive to operation of said control means upon sensing the leading edge of a document to connect said driving means to said second feeding means and being responsive to operation of said control means upon sensing the trailing edge of a document to connect said driving means to said first feeding means, and

20 (E) means operative associated with said clutch means and said first feeding means for limiting the operation of said first feeding means, while said clutch means is operative to connect said driving means to said first feeding means, to feed a sheet of paper from said storage means substantially only a distance sufficient to bring the leading edge of said sheet into operative engagement with said second feeding means whereby said sheet is moved from said storage means to said advanced position preparatory to a subsequent copying cycle of operation of the copying machine.

25 15. A combination according to claim 14 wherein said control means includes additional sensing means located in said first path of travel adjacent said second feeding means and operative to sense the passage of the trailing edge of a sheet of copy paper past said second feeding means, both said sensing means being operatively connected in said control means to cause the latter to maintain said clutch means engaged with said second feeding means until the trailing edge of both the document and the copy paper sheet have passed the sensing means located in their respective paths of travel.

30 16. In a copying machine having a storage means for a stack of sheets of copy paper, guiding and transporting means defining a path of travel for sheets of copy paper having an infeed end adjacent said storage means and extending through the copying machine and having an exposure zone spaced therealong from said storage means, means for continuously driving said transporting means and means including a source of illumination for projecting an image of indicia on an original document to said exposing zone while a sheet of copy paper is passing therethrough, the combination therewith of a mechanism for successively feeding sheets of paper from said storage means to said transporting means and for controlling the energization of said illuminating means, said mechanism comprising

35 (A) first feeding means disposed adjacent said storage means for feeding the topmost sheet from said stack into said infeed end of said guiding means,
 (B) second feeding means spaced along said path of

travel intermediate said infeed end thereof and said exposure zone, said second feeding means defining an advanced position for the leading edge of a sheet of copy paper,

(C) control means in said copying machine for initiating a copying cycle of operation and for sensing when the trailing edge of a sheet of copy paper has passed said second feeding means,

(D) clutch means responsive to said control means for alternately connecting said driving means to said first and second feeding means, said clutch means being responsive to operation of said control means when initiating a copying cycle of operation to connect said driving means to said second feeding means and being responsive to operation of said control means when sensing the passage of the trailing edge of a sheet past said second feeding means to connect said driving means to said first feeding means, and

(E) means operatively associated with said clutch means and said first feeding means for sequentially energizing said illuminating means when said clutch means is operated by said control means to connect said driving means to said second feeding means at the initiation of a copying cycle of operation and thereafter for simultaneously limiting the operation of said first feeding means, while said clutch means is operative to connect said driving means to said first feeding means, to feed a sheet of paper from said storage means substantially only a distance sufficient to bring the leading edge of said sheet into operative engagement with said second feeding means and for deenergizing said illuminating means substantially at the completion of said operation of said first feeding means whereby said sheet is moved from said storage means to said advanced position preparatory to a subsequent copying cycle of operation of the copying machine and said illuminating means is maintained energized during said movement of said sheet.

17. A combination according to claim 16 wherein said last named means comprises a switch connected to said illuminating means, and an intermittently operable drive transfer element coacting between said clutch means and said first feeding means and having means for automatically disengaging said driving means from said first feeding means independently of said control means when the leading edge of said sheet has been moved to said advanced position, said drive element also having means for closing said switch to energize said illuminating means when said clutch means is engaged with said second feeding means and for opening said switch to deenergize said illuminating means when said drive element disengages said driving means from said first feeding means.

18. A combination according to claim 17 wherein said last named means further comprises a spring loaded actuator operable in response to operation of said control means when initiating a copying cycle of operation of the copying machine to move said drive transfer element to a position where said driving means is reengaged with said first feeding means when said control means is operated upon sensing the movement of the trailing edge of a sheet of copy paper past said second feeding means, said drive transfer element including abutment means operatively associated with said switch for closing said switch upon movement of said drive transfer element by said spring loaded actuator and for opening said switch at the completion of operation of said drive transfer element when said first feeding means is disengaged from said clutch means by said drive transfer element.

19. A sheet feeding mechanism for successively pre-feeding sheets of paper from a supply stack to an advanced position and beyond comprising

(A) supply means for a stack of sheets of paper disposed at a first location,

(B) first feeding means operable to feed the topmost sheet from said stack,

(C) second feeding means disposed at a second location spaced from said first feeding means and adapted to receive a sheet from said first feeding means and to feed said sheet through said second feeding means,

(D) intermittently operable driving means connected to said first feeding means and operable when actuated to operate said first feeding to feed a sheet from said first location substantially only to said second location for operative engagement with the leading edge of said sheet by said second feeding means, and

(E) continuously operating shiftable driving means for alternately driving said first and second feeding means, said continuously operating driving means including

- (1) means under manual control for initially shifting said continuously operating driving means into engagement with said second feeding means,
- (2) sensing means for sensing when the trailing edge of a sheet has passed said second feeding means, and
- (3) means responsive to operation of said sensing means by the trailing edge of said sheet for shifting said continuously operating driving means from said second feeding means into driving engagement with said intermittently operable driving means,

whereby a subsequent sheet is fed from said first location to said second location immediately upon a preceding sheet being fed beyond said second location.

20. A mechanism according to claim 19 wherein said intermittently operable driving means comprises a drive transfer element having means for discontinuing driving operation of said drive transfer element after a predetermined amount of operation thereof and while said continuously operating driving means is engaged with said drive transfer element, and yieldable means responsive to operation of said manual control for resetting said drive transfer element to a position where said continuously operating driving means is drivingly engaged with said drive transfer element when said continuously operating driving means is shifted in response to operation of said sensing means by the trailing edge of a sheet.

21. A mechanism as set forth in claim 20 wherein said drive transfer element comprises a gear having circumferential teeth which mesh with the teeth of a second gear which is part of said continuously operating driving means and with a third gear connected to said first feeding means, an arcuate portion of the teeth of said drive transfer gear being cut away over a portion of the axial length of said gear to define a recess, said second gear being in alignment only with the recessed portion of said drive transfer gear whereby said drive transfer gear stops operating when said recess therein registers with said second gear.

22. A mechanism according to claim 21 wherein said gear includes cam means cooperating with said yieldable means for moving said gear a distance sufficient to move said recess away from a position of registration with said second gear when said second gear is shifted to said second feeding means in response to said manual control.
